UNITED STATES PATENT OFFICE.

GRANT C. MARSH, OF ST. LOUIS, MISSOURI, ASSIGNOR OF ONE-HALF TO WALTER F. KOKEN, OF ST. LOUIS, MISSOURI.

COOLING MEANS FOR ENGINES AND OTHER DEVICES.

1,330,207.

Specification of Letters Patent. Patented Feb. 10, 1920.

Application filed January 27, 1917. Serial No. 144,863.

To all whom it may concern:

Be it known that I, GRANT C. MARSH, a citizen of the United States, residing at St. Louis, Missouri, have invented a certain new and useful Improvement in Cooling Means for Engines and other Devices, of which the following is a full, clear, and exact description, such as will enable others skilled in the art to which it appertains to make and use the same.

This invention relates to a means for cooling engines and various other kinds of machines and structures that are provided with cylinders or other parts which it is necessary or desirable to cool.

One object of my invention is to provide an efficient cooling means for the purpose described that is less expensive to build, lighter in weight and easier to maintain in proper condition than a cooling system in which water or other liquid is used as the cooling medium.

Another object is to provide an air cooled engine or machine that will be cooled as effectively as an engine provided with a water cooling system, thereby overcoming the necessity of using high test cylinder oil, as is necessary with the air-cooled engines now in use. Other objects and desirable features of my invention will be hereinafter pointed out.

I have herein illustrated my invention embodied in an internal combustion engine of the type that is now generally used in automobiles, but I wish it to be understood that my invention is not limited to use with internal combustion engines, but, on the contrary, can be used with various other kinds of machines and devices which comprise parts that require cooling.

Briefly stated, my broad idea consists in arranging a jacket or casing over or around the part that is to be cooled, so as to form an air chamber, and then drawing air through said chamber by means of a suitable suction device, so as to absorb and carry away the heat that radiates from the part with which the air chamber co-operates. The particular construction of the jacket or element used to form the air chamber is immaterial, and it is also immaterial what means is employed for sucking or drawing air into and through said chamber.

Figure 1 of the drawings is a side elevational view of an internal combustion en-

gine constructed in accordance with my invention.

Fig. 2 is a front end elevational view of said engine.

Fig. 3 is a similar view, illustrating a slight modification of my invention.

Fig. 4 is a detail vertical sectional view, illustrating the construction of the air jacket used in the engine shown in Fig. 1.

Fig. 5 is a similar view, illustrating another way of forming said air jacket.

Fig. 6 is a vertical sectional view, illustrating an engine provided with an air jacket formed by a casing or shell that is mounted on the base or crank case of the engine, so as to completely incase the cylinders; and

Fig. 7 is a view, partly in side elevation and in vertical section, illustrating still another form of my invention.

Referring to Fig. 1 of the drawings, which illustrates one form of my invention, A designates the cylinders of an internal combustion engine, and B designates a jacket that is combined with said cylinders, so as to form an air chamber α into and through which air is drawn, so as to absorb and carry away the heat that radiates from the cylinders A. The jacket B of the engine shown in Fig. 1 is cast integral with the cylinders and is of substantially the same construction

as the water jacket of a water-cooled internal combustion engine. The particular construction of the jacket or casing that forms the air chamber α is immaterial, however, so far as my invention is concerned, and instead of being cast integral with the cylinders, as shown in Fig. 4, it can consist of a separate shell B' that is arranged over the upper portions of the cylinders, as shown in

Fig. 5, or a shell or casing B² that is mounted on the base or crank case of the engine, as shown in Fig. 6, so as to completely incase the cylinders and certain parts of the valve mechanism. The air chamber α is provided with one or more air inlets, and means is provided for sucking air into said chamber and causing the air to circulate through same, so as to absorb and carry away the heat that radiates from the cylinders of the engine. Preferably, the jacket, casing or part that forms the outer wall of the air chamber is provided with numerous holes, so that air will be drawn into the

chamber α at a sufficient number of points to obtain a constant supply of cool air to all portions of the chamber α . If desired, short, open-ended tubes 1 can be arranged in holes 5 in the jacket B, as shown in Figs. 1 and 4, so as to tend to cool the air by causing it to travel through numerous passageways of considerably greater length than their cross-sectional area in entering the air chamber α . 10 The inner end of the tubes 1 can either be spaced away slightly from the cylinders, or they can be arranged in engagement with the cylinders and provided at their inner ends with notches 1^a, as shown in Fig. 4, 15 through which the air escapes into the air chamber. The tubes 1 are not essential, however, as the air can be admitted directly to the air chamber α through holes 1^b formed in the jacket, as shown in Figs. 5 and 6, or 20 in any other manner. The jacket B can either be constructed in such a manner that it forms an air chamber for all of the cylinders, or each cylinder can be provided with a separate jacket, in which event the various 25 jackets will be connected with a manifold or manifolds, which, in turn, are connected with the suction device.

As previously stated, it is immaterial what means is used for drawing air into and 30 through the air chamber or chambers. In the form of my invention shown in Fig. 1, a rotary pump or fan C is used for this purpose, the inlet of the fan being connected by an intake pipe 2 with the air chamber α . 35 The intake pipe 2 is preferably provided with two branches or portions 2^a that lead to the opposite sides of the air chamber α , so as to insure an adequate supply of cooling air to all portions of the cylinders of the 40 engine. The suction device C can be operated in any suitable manner and arranged in any desired position, but it is preferably arranged at the front of the engine and operated from the crank shaft 3 of the engine by gears or a chain 4. Instead of using 45 a fan or pump C for drawing the cooling air into and through the air chamber or chambers, the carburetor C' of the engine can be used as the suction device of my improved cooling system. Therefore, in Fig. 3 of the 50 drawings I have illustrated another form of my invention, wherein the air intake pipe 2 leads to the air inlet of the carburetor C', which may be of any preferred type. When 55 the carburetor of the engine is used as the suction device, the cost of manufacturing the engine is, of course, reduced, and another advantage that results from using the carburetor as the suction device, is that the 60 air admitted to the carburetor to vaporize the liquid fuel is preheated, thus overcoming the necessity of equipping the carburetor or the engine with a separate air heating means, as is now the usual practice.

65 In order that the engine may be main-

tained at the temperature at which it operates most efficiently, I have provided my improved cooling system with a means for varying or regulating the supply of air to the air chamber or chambers that coöperate with the part or parts to be cooled. In the form of my invention herein shown said means consists of valves 5 arranged in the two branches of the air intake pipe 2 and controlled by rods or other devices 6 that 75 preferably lead to a point in proximity to the operator in charge of the engine. It will, of course, be understood that various other means can be used for controlling the supply of cooling air to the system without departing from the spirit of my invention. 80

In most automobiles the exhaust pipe 7 of the engine extends underneath the floor boards of the driver's compartment and heats said floor boards and compartment 85 to such a degree in warm weather that it is very objectionable to the occupant. My improved cooling system enables this objectionable feature of automobiles to be remedied easily, by simply arranging a 90 perforated jacket or casing 8 over the portion of the exhaust pipe that extends under the floor boards, as shown in Fig. 1, and connecting the interior of said jacket by means of a pipe 9 with the air 95 inlet pipe that leads to the suction device of the system. If desired, the pipe 9 may be provided with a valve 10 for controlling the supply of air that is drawn into and through the jacket 8. When a suction device, 100 separate and distinct from the carburetor, is used, the discharge side of said suction device can be connected by means of a pipe 11 with a foot warmer or other heating device (not shown) arranged at any 105 desired point inside of the automobile.

Air at normal temperature, when drawn into and through the air chamber α in the manner described, will effectively cool the engine, but if desired, means may be used 110 for cooling the air before it is admitted to said air chamber. One efficient air cooling means that may be used consists of a member 12, formed of material that is more or less porous, and a receptacle 13 surrounding 115 said member 12 and filled with water, as shown in Fig. 7; the member 12 being so constructed that air will be drawn through same when the suction device of the system is in operation. In the form of my invention shown in Fig. 7 the member 12 has a center hole 12^a that extends longitudinally through same, and said member 12 is mounted on an air inlet pipe 14 in one end of the receptacle 13, and an air pipe 14^a that leads 120 from the opposite end of said receptacle to a manifold 15. Branch pipes 16 lead from said manifold 15 to short tubes 1 in the jacket A, so as to cause fresh air to be drawn into the member 12, cooled and also 130

moistened slightly, in traveling through said member, and thereafter supplied to the air chamber α , so as to absorb and carry away the heat that radiates from the cylinders.

5 An air cooling system of the character above described can be used successfully on internal combustion engines, steam engines, compressors and other kinds of machines for 10 cooling the cylinders, and it can be used with various other kinds of devices for cooling parts which require cooling, such, for example, as with cannons and machine guns. When used on an automobile engine, it materially reduces the weight and cost of 15 manufacturing the automobile, as it overcomes the necessity of using a radiator. When combined with an internal combustion engine it produces a more efficient air 20 cooled engine than any air cooled engine now in use, as it cools the cylinders so effectively that it is not necessary to use high test cylinder oil to lubricate the engine.

Having thus described my invention, 25 what I claim, and desire to secure by Letters Patent, is:

1. An internal combustion engine provided with a cylinder, a jacket combined

with said cylinder to form an air chamber, open-ended tubes carried by said jacket and 30 arranged with their inner ends butting against the outside of the cylinder, said tubes being provided at their inner ends with notches, a suction pump operated by the engine for drawing air into said chamber through said tubes and the notches at 35 the inner ends of same and then drawing said air out of said chamber after it has absorbed heat from the cylinder, an exhaust pipe, a perforated jacket arranged over a 40 portion of said exhaust pipe, and a connection between said suction pump and said perforated jacket; for the purpose described.

2. An internal combustion engine, comprising an air jacket combined with the 45 cylinders, an air cooling means consisting of a porous member arranged in a water receptacle, said porous member having an air passageway in same which communicates with the atmosphere, and means for causing 50 air to travel through the air passageway in said porous member and then circulate through said air jacket so as to absorb and carry away the heat that radiates from the cylinders.

GRANT C. MARSH.
